UNITED STATES PATENT OFFICE.

JOHN R. FORTUNE, OF DETROIT, MICHIGAN.

FURNACE.

979,661.

Specification of Letters Patent. Patented Dec. 27, 1910.

Application filed March 12, 1910. Serial No. 548,953.

To all whom it may concern:

Be it known that I, JOHN R. FORTUNE, a citizen of the United States of America, residing at Detroit, in the county of Wayne 5 and State of Michigan, have invented certain new and useful Improvements in Furnaces, of which the following is a specification, reference being had therein to the accompanying drawings.

10 This invention relates to improvements in automatic stokers and more particularly to a grate especially adapted for burning anthracite and other of the smaller sizes of coal, and means for automatically operating 15 the grate.

The object of the invention is to provide a cheap construction of grate formed of stationary and movable bars, said movable bars being provided with means forming a continuous movable ledge or shelf for feeding the coal from the hopper and each bar being provided with suitable air passages to prevent its destruction by the heat.

A further object is to provide simple and 25 efficient means for actuating the movable bars which means is adapted to move certain of the bars a greater distance than others; and to provide certain other new and useful 30 features in the construction and arrangement of parts, all as hereinafter more fully described reference being had to the accompanying drawings in which,

Figure 1 is a transverse vertical section 35 through a furnace embodying the invention; Fig. 2 is a sectional perspective detail of a portion of one side of the furnace; Fig. 3 is a perspective view of a rock shaft for operating movable grate bars; Fig. 4 is a perspective detail of one of the fixed grate bars; 40 Fig. 5 is a similar view of one of the movable grate bars; and Fig. 6 is a perspective view of one of the two parts or halves of the same.

In the drawings, a smoke consuming furnace of the usual construction is shown, comprising side walls 1 adjacent to which are hoppers 2, one side of each of which is formed by an arch plate 3 for supporting the inner and outer arches 4 and 5 spanning the space between the hoppers.

50 6 is an ash pit above which is supported a grate bearer 7 having bearings for the usual rotatable clinker bar 8 supported within the bearer and extending longitudinally thereof.

Two inclined grates are each composed of 55 independent grate bars supported with their

upper ends beneath one of the hoppers 2 and their lower ends resting upon flanges 9 extending laterally from the sides of the bearer 7. These grates consist of a series of alternating fixed and movable bars 10 and 11 respectively, the fixed bars being each provided with a flanged end 12 to engage a suitable rib 13 on the outer wall of the hopper near its lower end, where it is bolted or otherwise secured in place with its lower end resting 60 upon the flange 9 of the grate bearer. A main vertical web 14 is stepped or formed with a series of notches in its upper edge and provided with laterally extending flanges at the upper edge of each notch or step to form 65 a series of fuel supporting shelves 15. Ribs 16, projecting laterally from each side of the web, form continuations of the flanges forming each shelf and extend beneath the shelf above to form air passages 17 through the 70 grate beneath each shelf for cooling the same and to prevent the fuel from dropping through. In the upper end of the web 14 of each stationary bar is a hole 18 forming a bearing for a rock shaft 19 which extends 75 transversely of the bars through the openings therein and is provided with a laterally extending rib 20, the opening 18 in each bar being formed with a lateral extension 21 for the rib 20 to permit the same to turn therein 80 and allow the rock shaft to be rocked.

Each of the movable bars 11 consists of two like parts or halves, each part comprising a vertical web 22 which is stepped or notched in its upper edge in a manner similar to the fixed bars and is formed with ribs 23 extending laterally therefrom toward the similar ribs on the other web of the bar to space the webs apart and form an air space 90 within the bar, said ribs being integral with the web at the upper edges of the steps or notches and meeting the corresponding ribs on the other half of the bar to form narrow fuel supporting ledges or shelves 24. The ribs are each extended rearwardly from each shelf beneath the shelf above to form air 95 passages 25 within the bar opening through the bar beneath one end of each shelf and above the opposite end of the shelf below. The rearwardly extended portions of the ribs also prevent the fuel from falling through the grate through the open ends of said passages. The two halves of the bar may if found desirable, be secured together 100 with the edges of the ribs 23 in contact, by 105 110

bolts or rivets 26 and at the upper end of the bar, each web 22 is formed with a notch 27 in its lower edge to engage the rib 20 on the rock shaft 19. The movable bars are thus supported at their upper ends by resting upon the rock shaft 19 and each engages and slides upon the flange 9 of the grate bearer at its lower end between two adjacent fixed bars, the edges of the ribs 16 of which engage the plain outer sides of the two adjacent movable bars, which bars close and form one side of the air passages 17 of the fixed bars. At its extreme upper end, each half of each movable bar is formed with an integral plate, which plates on the halves together form a shelf 28, with the inner edges of the plates held in contact with each other and the outer edges of the plates are extended laterally beyond the sides of the webs and overlap the upper shelves 15 of the two adjacent fixed bars to meet the shelves on the adjacent movable bars and form a continuous shelf across the upper end of the grate. End portions 29, formed integral with the inner end of each shelf 28 and of the same width as said shelf, extend downward, meeting the upper surface of the shelf 24 below, and form vertical end walls for the shelves overlapping the adjacent shelves 15 of the adjacent fixed bars. When the fixed and movable bars are all in place within the grate, the continuous shelf formed by the several shelves 28 moves forward and back with the movable grate bars beneath the bottom plate 30 of the hopper above, forming a stoker to receive the fuel from the mouth of the hopper and push the same inward on to the shelves below of the several grate bars where it is gradually fed downward by the forward and backward movement of the movable bars.

Preferably the movable bars are never moved rearwardly beyond the ends of the shelves 15 of the fixed bars and thus the sides of the air passages 17 are always closed, causing the air to pass through said passages in contact with the lower surfaces of the shelves throughout their entire length and preventing the burning off of the forward corners of said shelves. The movable bars being in effect, formed hollow with internal air passages 25 directing the air against the under surface of each shelf and opening through the bars at the inner ends of said shelves, said shelves are cooled in every position of the bars by the air passing therethrough and the projecting corners are prevented from burning off.

In practice it is found that it is desirable to move those movable grate bars which are near the forward and the rear furnace walls at the ends of the grates, a greater distance than those near the middle of the grate, so that the fuel will be given a greater impetus near the walls, overcoming the frictional re-

sistance to the downward movement of the fuel by its engagement with said walls. To accomplish this in a cheap and convenient manner, the rib 20 on the rock shaft 19 is made of varying width, it being considerably narrower radially of the shaft, intermediate its ends than toward each end, and thus when the rock shaft is turned to actuate the movable bars, those bars which engage the narrower portion of the rib will not be given as great a throw as those nearer the furnace walls at the ends of the grate.

The construction of grate described is cheap to manufacture and is very efficient in burning anthracite or other small forms of coal, and by making the upper ends of the movable grates in such a way that they form a continuous shelf or stoker for moving the fuel from the hopper, the necessity for separate means for feeding the fuel to the grate bars is obviated. The construction of the bars being such that all projecting corners are at all times cooled by air currents passing through the bars, said bars are effectually prevented from being destroyed by the heat and an ample air supply is provided throughout the entire area of the grates permitting the placing of the bars close together so that fine fuel will not fall through.

Having thus fully described my invention what I claim is:

1. In a device of the character described, the combination of a hopper, inclined stationary grate bars, inclined movable grate bars alternating with the stationary bars, and means carried by the upper ends of the movable bars overlapping the stationary bars and forming a continuous shelf at the upper end of the grate movable with the movable bars.

2. In a device of the character described, the combination of a hopper, inclined stationary grate bars supported with their upper ends beneath the hopper, inclined movable grate bars alternating with the stationary bars, and a shelf carried by the upper end of each movable bar movable therewith beneath the hopper and extending laterally over each adjacent stationary bar to meet the edges of the shelves on the adjacent movable bars, said shelves together forming a continuous stoker to receive fuel from the hopper and feed the same on to the grate bars.

3. In a device of the character described, the combination of a hopper, a series of stationary inclined grate bars each having a stepped upper surface, forming shelves for supporting fuel, movable inclined bars between the stationary bars each having a stepped upper surface, a shelf on the upper end of each movable bar projecting laterally over the adjacent stationary bars to meet the shelves on the adjacent movable bars and form a continuous shelf across

the upper end of the grate beneath the hopper, and means for actuating the movable bars simultaneously in the same direction.

4. In a device of the character described, the combination of a hopper, a series of stationary grate bars having stepped upper surfaces, a series of movable grate bars alternating with the stationary bars and having stepped upper surfaces, a shelf on the upper end of each movable bar to receive fuel from the hopper and extending over the upper steps of the adjacent stationary bars, and a wall extending downward from the edge of the shelf on each movable bar to the step below on said bar and forming means for moving the fuel.

5. In an automatic stoker, the combination with a hopper and a series of movable grate bars, of a rock shaft extending across said series of bars, and laterally extending means on the rock shaft adapted to engage and operate the bars, said means extending laterally from one portion of the shaft to a greater distance than from other portions thereof to give to certain of the grate bars a greater movement than to the others.

6. In an automatic stoker, the combination with a hopper and a series of movable grate bars, of a rock shaft extending transversely of said bars, and a rib on said shaft extending longitudinally thereof and projecting a greater distance radially therefrom at one portion of the shaft than at other portions thereof to engage and move said bars of the series different distances when the shaft is turned.

7. In an automatic stoker, the combina-

tion with a hopper and a series of movable grate bars, of a rock shaft extending transversely of said bars, and a radial rib extending longitudinally of said shaft and projecting radially a greater distance therefrom near each end of the shaft than intermediate the ends thereof to engage and move said bars, and means for turning the shaft.

8. In a device of the character described, the combination of a series of stationary grate bars each having a central vertical web stepped at its upper edge and formed with ribs projecting laterally from each side forming a series of shelves, a series of movable grate bars alternating with the stationary bars and each formed of separate parts and having parallel vertical webs having plain outer surfaces engaged by the ribs on the adjacent stationary bars and provided with meeting ribs on their adjacent surfaces forming a series of shelves and spacing the webs to form an air passage beneath each shelf opening through the bar, said ribs on the stationary bars also forming air passages opening through said stationary bars beneath each shelf, means for securing the parts of each movable bar together and means for actuating the movable bars.

In testimony whereof I affix my signature in presence of two witnesses.

JOHN R. FORTUNE.
